UNITED STATES PATENT OFFICE.

MARTIN ENGERS, OF TORONTO, ONTARIO, CANADA.

LAMP-DIMMER.

1,146,143.

Specification of Letters Patent.

Patented July 13, 1915.

Continuation of application Serial No. 778,045, filed July 9, 1913. This application filed April 4, 1914, Serial No. 829,696. Renewed April 9, 1915. Serial No. 20,323.

To all whom it may concern:

Be it known that I, MARTIN ENGERS, a British subject, and resident of the city of Toronto, in the county of York and Province of Ontario, in the Dominion of Canada, have invented certain new and useful Improvements in Lamp-Dimmers; and I do hereby declare that the following is a full, clear, and exact description of same.

10 My invention relates to an illuminating means comprising a source of light, a reflector therefor, and an adjustable shutter which can be selectively moved to an open position for the radiation of all the direct 15 and reflected rays or to a partly closed position for the radiation of all the direct rays and part of the reflected rays or to a closed position to intercept all of the reflected rays, the objects of my invention being: (a) to 20 construct this shutter of a series of arc-shaped sections, each of which is pivotally fixed at one end to a stationary part of the illuminating means and is provided at the other end with a projection having a limited 25 movement in a radially slotted adjusting ring for moving the arc-shaped sections to their adjusted position and maintaining them in such position until it is again moved; and (b) to provide the adjusting 30 ring with suitable stopping elements which will determine the limits of the opening and closing movements of the shutter.

For an understanding of my invention reference is to be had to the following description and to the accompanying drawings, in which:

Figure 1, is a vertical section of a lamp provided with an adjustable shutter in front of the source of light for controlling the reflected and direct rays, the shutter in this view being shown in its closed position. Fig. 2, is a front elevation of the shutter, in a partly closed position, showing the adjusting ring and its connections with the 45 shutter sections, this view also showing the stops for arresting the adjusting ring when it reaches its limit of movement in either an opening or closing direction. Fig. 3, is a broken view similar to Fig. 2, showing the 50 shutter in its closed position. Fig. 4, is a broken view showing the shutter in its fully opened position. Fig. 5, is a plan view of the stops for arresting the movement of the adjusting ring, and Fig. 6, is a detail view 55 of one of the shutter sections.

Like characters of reference refer to like parts throughout the specification and drawings.

Within the casing 1 is a reflector 2 and a source of light 3, shown in Fig. 1 to be an incandescent electric lamp fixed in a holder or socket 4 in the center of the reflector 2. Fixed within the casing 1 is a stationary ring or annulus 1^a and pivotally connected at 5° to the ring or annulus 1^a are the relatively stationary ends of the arc-shaped sections 5^a constituting the diaphragm of the shutter. These arc-shaped sections 5^a are preferably of such curvature that when the shutter is moved to its fully opened, or partly closed, position the inner edges of these sections will form a substantially true circle as shown in Figs. 2, 3 and 4 of the drawings, so that the projected rays will in all cases take the form of a cylindrical beam of uniform intensity throughout its cross sectional area. When the shutter sections 5^a are moved from their open position they overlap each other and form a substantially imperforate diaphragm as shown in Figs. 2 and 3, to intercept the reflected rays from the source of light.

As shown in Fig. 1, the shutter sections 5^a are in front of the source of light for intercepting the reflected rays when the shutter is moved to its partly closed or fully closed position, but the shutter may be positioned between the source of light and the reflector.

At the free end of each of the arc-shaped sections 5^a is a pin 7 operating in a radial slot 8 in the adjusting ring 9. This adjusting ring is rotatable in guides 10 connected to the stationary annulus 1^a, and during its rotation carries with it the free ends of the arc-shaped sections 5^a, the slots 8 being provided for the change of position of the pins 7 with relation to the adjusting ring as the latter rotates.

During the rotation of the adjusting ring in the direction indicated by arrow in Fig. 2, the arc-shaped sections are moved to contract the opening 6 and if the movement of the adjusting ring in this direction is continued to its limit of motion the opening 6 will be contracted to the dimensions shown in Fig. 3, which, for ordinary purposes, is sufficient to intercept all of the reflected rays without intercepting the direct rays. The stop 12 for the adjusting ring, if desired,

may be so positioned that the arc-shaped sections can be moved to completely close the opening through the shutter so that neither the direct nor the reflected rays can be projected.

When the adjusting ring is moved in the opposite direction to that indicated by arrow in Fig. 2, the arc-shaped sections are positioned to increase the size of the opening through the shutter until the shutter assumes the position shown in Fig. 4.

As shown in Fig. 2, the annulus or stationary ring 1^a is provided with two fixed stops 11 and 12 respectively, and the adjusting ring 9 is provided with a stop 13 revolvable in unison with the ring and employed to engage the stationary stops 11 and 12 to arrest the movement of the adjusting ring when it comes into contact with either of said stops and thus limit the movement of the shutter in an opening or closing direction respectively.

Connected to the stop 13, is a cable 15 by means of which the adjusting ring is moved in a shutter-closing direction, and connected to the stop 13 is a spring 16 by means of which the adjusting ring is moved in a shutter-opening direction, the force of the spring being sufficient to cause the instantaneous movement of the adjusting ring and shutter when relieved of the counter-acting force of the cable. By means of this device it is possible to selectively move the shutter to a fully opened position for the radiation of all the direct and reflected rays, or to move it to a partly closed position for the radiation of all the direct rays and part of the reflected rays, or, to a closed position to intercept all of the reflected rays.

Having thus fully described the nature of my invention, what I claim as new and desire to secure by Letters Patent, is:—

1. The hereinbefore described device comprising a reflector, a source of light, and an adjustable shutter selectively movable to an open position for the unobstructed radiation and reflection of all the light rays, or to a closed position for intercepting all or part of the reflected rays, said shutter comprising a rotatable adjusting ring having a series of radial slots therein, and a series of arc-shaped shutter sections one end of each of which is pivotally fixed, and the other end of each of which is movable and provided with a projection contained in one of said radial slots, said adjusting ring during its rotation engaging said projections and selectively moving the shutter sections to an open or closed position.

2. The hereinbefore described device comprising a reflector, a source of light, and an adjustable shutter selectively movable to an open position for the unobstructed radiation and reflection of all the light rays, or to a closed position for intercepting all or part

of the reflected rays, said shutter comprising a rotatable adjusting ring having a series of radial slots therein, and a series of arc-shaped shutter sections one end of each of which is pivotally fixed, and the other end of each of which is movable and provided with a projection contained in one of said radial slots, said adjusting ring during its rotation engaging said projections and selectively moving the shutter sections to an open or closed position, two fixedly positioned stops, and a stopping member for the adjusting ring to engage said stops and arrest the movement of the adjusting ring when it has reached its limit of motion in either an opening or closing direction.

3. The hereinbefore described device comprising a reflector, a source of light, and an adjustable shutter selectively movable to an open position for the unobstructed radiation and reflection of all the light rays, or to a closed position for intercepting all or part of the reflected rays, said shutter comprising a rotatable adjusting ring having a series of radial slots therein, and a series of arc-shaped shutter sections one end of each of which is pivotally fixed, and the other end of each of which is movable and provided with a projection contained in one of said radial slots, said adjusting ring during its rotation engaging said projections and selectively moving the shutter sections to an open or closed position, two fixedly positioned stops and a stopping member for the adjusting ring to engage said stops and arrest the movement of the adjusting ring when it has reached its limit of motion in an opening or closing direction, said stops and stopping members being clear of the path of the direct and reflected rays from the source of light and reflector.

4. The hereinbefore described device comprising a reflector, a source of light, and an adjustable shutter selectively movable to an open position for the unobstructed radiation and reflection of all the light rays, or to a closed position for intercepting all or part of the reflected rays, said shutter comprising a rotatable adjusting ring having a series of radial slots therein, and a series of arc-shaped shutter sections one end of each of which is pivotally fixed, and the other end of each of which is movable and provided with a projection contained in one of said radial slots, said adjusting ring during its rotation engaging said projections and selectively moving the shutter sections to an open or closed position, and means for causing the rotation of the adjusting ring to effect the opening and closing movements of said shutter sections.

5. The hereinbefore described device comprising a reflector, a source of light, and an adjustable shutter selectively movable to an open position for the unobstructed radiation

and reflection of all the light rays, or to a closed position for intercepting all or part of the reflected rays without intercepting the direct rays, said shutter comprising a rotatable adjusting ring having a series of radial slots therein, and a series of arc-shaped shutter sections one end of each of which is pivotally fixed, and the other end of each of which is movable and provided with a projection contained in one of said radial slots, said adjusting ring during its rotation engaging said projections and selectively moving the shutter sections to either an open or closed position, two fixedly positioned stops 10 and a stopping member for the adjusting ring to engage said stops and arrest the movement of the adjusting ring when it has reached its limit of motion in either an opening or closing direction, and means for causing the rotation of the adjusting ring to effect the opening and closing movements of said shutter sections.

6. The hereinbefore described device comprising a casing, a reflector and a source of light therein, a stationary annulus opposed to the reflector, an adjustable shutter comprising a series of arc-shaped shutter sections each pivotally fixed at one end to said annulus and having a projection at the other end, a rotatable adjusting ring opposed to the annulus and having a radial slot therein for each of said projections whereby the adjusting ring will engage said projections and selectively cause the opening and closing movements of said shutter sections, and stops to arrest the movement of the adjusting ring when it has reached its limit of motion in either direction, said stops being clear of the path of the direct and reflected rays from the source of light.

7. The hereinbefore described device comprising a casing, a reflector and source of light therein, a stationary annulus opposed to the reflector, an adjustable shutter com-

prising a series of arc-shaped shutter sections each pivotally fixed at one end to said annulus and having a projection at the other end, a rotatable adjusting ring opposed to the annulus and having a radial slot therein for each of said projections whereby the adjusting ring will engage said projections and selectively cause the opening and closing movements of said shutter sections, stops to arrest the movement of the adjusting ring when it has reached its limit of motion in either direction, said stops being clear of the path of the direct and reflected rays from the source of light, and means for actuating the adjusting ring to effect the opening and closing movements of the shutter sections.

8. The hereinbefore described device comprising a casing, a reflector and a source of light therein, a stationary annulus opposed to the reflector, an adjustable shutter comprising a series of arc-shaped shutter sections, each pivotally fixed at one end to said annulus and having a projection at the other end, a rotatable adjusting ring opposed to the annulus and having a radial slot therein for each of said projections, whereby the adjusting ring will engage said projections and selectively cause the opening and closing movements of said shutter sections, stops to arrest the movement of the adjusting ring when it has reached its limit of movement in either direction, said stops being clear of the path of the direct and reflected rays from the source of light, means for selectively moving the adjusting ring in one direction, and spring-pressed means for moving it in the opposite direction.

Dated this fourth day of March, A. D. 1914.
